US00D916076S

(12) **United States Design Patent** (10) **Patent No.:** **US D916,076 S**
(45) **Date of Patent:** **** Apr. 13, 2021**

(54) **NOTEBOOK**

(71) Applicant: **Samsung Electronics Co., Ltd.**, Suwon-si (KR)

(72) Inventors: **Hoyoung Seoc**, Seoul (KR); **Iksang Kim**, Seoul (KR); **Seungho Jung**, Seoul (KR)

(73) Assignee: **Samsung Electronics Co., Ltd.**, Suwon-si (KR)

(**) Term: **15 Years**

(21) Appl. No.: **29/680,218**

(22) Filed: **Feb. 14, 2019**

(30) **Foreign Application Priority Data**

Nov. 7, 2018 (KR) 30-2018-0051308

(51) **LOC (13) Cl.** **14-02**

(52) **U.S. Cl.**

USPC **D14/315**

(58) **Field of Classification Search**

USPC D14/371, 376, 315-327, 341, 439; D3/900; 361/679.09, 679.26-679.27

(57) **CLAIM**

We claim the ornamental design for a notebook, as shown and described.

DESCRIPTION

FIG. 1 is a top perspective view of a notebook showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a bottom perspective view thereof.

The broken lines in the figures depict portions of the notebook which form no part of the claimed design.

1 Claim, 4 Drawing Sheets
